C. TEMME.

COOKING STOVE.

No. 245,673.

Patented Aug. 16, 1881.

ATTEST:

Robert Burns
E. L. Morse

INVENTOR:

Christian Temme

UNITED STATES PATENT OFFICE.

CHRISTIAN TEMME, OF ST. LOUIS, MISSOURI.

COOKING-STOVE.

SPECIFICATION forming part of Letters Patent No. 245,673, dated August 16, 1881.

Application filed March 28, 1881. (No model.)

To all whom it may concern:

Be it known that I, CHRISTIAN TEMME, a citizen of the United States, residing at St. Louis, in the State of Missouri, have invented 5 a certain new and useful Improvement in Cooking Stoves or Ranges, of which the following is a specification.

My invention relates to certain improvements in side-flue cooking stoves or ranges, 10 and has for its object a more even and perfect distribution of the heat over the bottom of the oven, to thus prevent the overheating of the center portion of the oven, which is a serious defect usual to the ordinary side or three flued 15 cooking-stove. I attain this object by the construction illustrated in the accompanying drawings, in which—

Figure 1 is a longitudinal section; Fig. 2, a sectional plan view at line $x x'$; Fig. 3, a trans- 20 verse section at line $x' x'$, and Fig. 4 a detail transverse section at line $x^2 x^2$.

Similar letters of reference refer to similar parts throughout the several views.

In the drawings I have illustrated my invention 25 as applied to the ordinary form of three-flue cooking stove or range.

The first novel feature of my invention consists in the provision of a casing, A, arranged at the bottom and side of the stove, as shown, 30 so as to form a diving and outlet flue, B, which communicates with the center flue, C, under the bottom of the stove and extends up the side of the stove, and is provided with a collar, as usual, for the attachment of the stove-pipe.

The second novel feature of my invention 35 consists in forming the back flue, D, continuous across the stove with inclined deflecting plates or partition d for deflecting the heated gases, smoke, &c., into the side flues, E E, as clearly 40 indicated in Fig. 4.

F is a damper controlling the discharge of

the heated gases, &c., either directly into the outlet-flue B or into the stove-flues D E E, as required.

The action of my improvement is as follows: 45 The heated gases, &c., passing down the back flue, D, are deflected by plates d into the side flues, E, and passing along through the same are discharged at front into the center flue, C, from which flue C they pass into the diving 50 outlet-flue B in manner indicated by arrows on the drawings.

The main advantage derived from my improvement is that it more effectually and evenly distributes the heat over the bottom of the 55 oven, and thus prevents the overheating of the central portion of said oven, which is a very objectionable feature met with in the ordinary three-flue cooking-stove.

Having thus fully described my said invention, what I claim as new, and desire to secure by Letters Patent, is—

1. A three-flue cooking stove or range provided with an exit-flue, B, communicating with the center flue, C, and extending transversely 65 across the bottom from the center flue and up the side of the stove, as described, and for the purpose set forth.

2. A cooking stove or range having its back flue continuous across the stove, and inclined 70 plates or partitions d , in combination with the bottom flues, C E E, and exit-flue B, all arranged substantially as herein described, and for the purpose set forth.

In testimony of said invention witness my 75 hand at St. Louis, Missouri, this 23d day of March, 1881.

CHRISTIAN TEMME.

In presence of—

ROBERT BURNS,
A. C. SCHUHMAN.
